UNITED STATES PATENT OFFICE.

FRANZ RAUCHWETTER, DECEASED, LATE OF BERLIN, GERMANY; BY ANNA RAUCHWETTER, NEE BÖHME, ADMINISTRATRIX, OF BERLIN, FRIEDENAU, GERMANY, ALFRED FLATER, PRESENT ADMINISTRATOR OF THE ESTATE OF SAID FRANZ RAUCHWETTER, DECEASED.

TRANSFER MECHANISM FOR CALCULATING MACHINES.

Application filed May 19, 1921. Serial No. 471,014.

To all whom it may concern:

Be it known that FRANZ RAUCHWETTER, deceased, late a citizen of the German Republic, and residing at Berlin, Friedenau, Germany, has invented certain new and useful Improvements in Transfer Mechanism for Calculating Machines, of which the following is a specification.

This invention relates to calculating machines of the type, in which the counter is raised and lowered in order to bring the gear wheels of the said counter out of, or into, engagement with the toothed gearing actuating sectors or the like, operated from the key board or equivalent part of the machine.

A calculating machine of this kind is described and shown in the United States patent-specification No. 1,239,622. There the racks of the transfer-mechanism are lifted and lowered.

The present invention now relates to the provision of a novel kind of a tens transfer mechanism in calculating machines of a similar type, the arrangement being such that the counting mechanism, by lowering it, is made to engage racks of the transfer-mechanism, whereas by lifting the counting mechanism this latter is disengaged from those racks.

It has been found in practice that with calculating machines of the type mentioned in the first paragraph after the preamble in general and in the second paragraph in particular, more especially when they are driven mechanically, for instance by an electric motor, there is a tendency for inaccuracies to be caused—due to the momentum of the parts.

The primary object of the present invention is to provide means in connection with the transfer mechanism, for ensuring the accurate working of the machine, whether simple numbers are being transmitted to the counter, without a transfer taking place, or when a transfer is taking place from one numerical place to the next, or through several numerical places.

To prevent overrunning of the counting mechanism, it has already been proposed to utilize the racks for preventing overrunning as driving elements for carrying through the operation of the transfer mechanism.

It has also been proposed to so construct the operating and transfer devices of a totalizing counter that the counter is in engagement with one or other of the said devices at all periods of operation. 55

The characteristic feature of the invention consists in connecting to the arms or levers supporting the counter mechanism, the racks which on the one hand operate the transfer and on the other hand lock the toothed wheel from overrunning, so that on lowering or raising the counter the engagement or disengagement as the case may be of the locking or transfer racks with the wheels of the counter is effected. 60

Other features of the invention will be pointed out in the following description:— 70

In order that our said invention may be more clearly understood, we will now proceed to describe the same with reference to the accompanying drawings, which show, by way of example, one method of carrying it 75 into practical effect.

Fig. 1 is a side elevation of the actuating gear of the counter in a position just before the transfer takes place.

Fig. 2 is a corresponding front elevation. 80

Fig. 3 is a side elevation showing the position of the parts ready for the transfer, that is to say with the transfer lever set into position.

Fig. 4 is a side elevation showing the 85 position just after the transfer has taken place.

Figs. 5, 6, and 7 show the mechanism for restoring the locking racks to their original position. 90

In Figs. 1 and 2, 1 represents the number discs of the counter, provided with the numbers 0-9. These number discs are driven in a well known manner by toothed gearing 2, 2¹, for each numerical unit, 2 denoting the gearing for addition, and 2¹, the gearing for subtraction. 3 is the corresponding actuating sector, operated from the key board or the like and adapted to drive the counter gearing in the positive 100 direction for addition or in the negative direction for subtraction whenever the gearing of the counter is engaged with the actuating sector 3, by the lowering of the said counter, as illustrated at Fig. 3. 105

Each of the number discs is provided with

a pin 4 of the usual description for effecting the transfer, which co-operates with the transfer lever 6 pivotally mounted at 5.

For this purpose the transfer lever 6 is provided with a V shaped projection 7, which projects into the path of the pin 4, in such a way that when the number disc 1 is turned in the direction for adding, that is to say in the direction indicated by the arrow 8, the upper surface of the V is pushed aside by the pin 4, while when the disc is moved in the direction of the arrow 9, the direction for subtraction, the lower edge of the V shaped projection 7 is operated by the pin.

In its normal position, as shown at Fig. 1, the lever 6 is held in position by means of a bent lever 11 pivotally mounted at 10 and connected to the lever 6 by a spring 12. This is effected by the forward edge of the lever 6 coming against a projection 13 of the bent lever 11. As soon as the pin 4 (Fig. 3) has passed the V shaped projection 7 and has pushed the lever 6 outwards, the said lever is locked in this position by a projection 14 on the lever 6 coming against a shoulder 15 on the bent lever 11, as shown at Fig. 3. In this position the lever 6 is ready for the transfer.

For locking the counter discs during the time when the gearing for operating these discs is out of engagement with the actuating segments 3, locking racks 16, and 16¹ are provided. In the preferred embodiment these are formed as a double rack for each unit of the counting mechanism. One of these racks, in the adding position engages the gear 2¹ for subtraction in the counter, while the other at the same time is disengaged, see Fig. 2. In the position of the counter for subtraction, on the other hand, the rack 16 engages the adding gear 2, while the rack 16¹ is disengaged from the subtraction gear 2¹.

It will be understood that the counter is so constructed and mounted in a well known manner that to alter from addition to subtraction, it is simply necessary to shift it laterally. The toothed rack, on the other hand, cannot be moved laterally.

The toothed sector for transmitting individual numbers from the key board or setting mechanism is located between the locking racks 16 and 16¹ and, in the position for addition, engages the gearing 2 of the counter, while in the position for subtraction it engages the gear 2¹. As long as the rack 16 is in engagement with the gearing 2 of the counter, no rotation of the same can be effected, in fact the counter mechanism is locked immovably in position by this rack.

24 is a bent lever, pivotally mounted at 23, and 25 is a tension spring, which tends to press the end of the lever 24 against a projection 21^a on a spring controlled arm 21. When the arm 21 is pressed outwards,

as hereinafter fully explained, the support for the bent lever 24 falls away, so that this lever can swing outwards until it comes against a second projection 26 of the bent lever 21.

As however the toothed racks 16 are hinged to the upper or vertical arm of the bent lever 24, they are pushed forward through a division corresponding to one figure plate on the number disc of the counter, and in the opposite direction to the movement of the toothed sector 3, when transmitting a number from the setting mechanism. As however in the position for addition the toothed rack 16¹ engages the subtraction gear 2¹ of the counter, the transfer mechanism is moved through the toothed rack 16¹, which has been moved through a distance corresponding to one numerical place in the opposite direction to the toothed sector 3, but in the correct direction when carried over to the counting discs.

It is to be understood that the arrangement is such that the transfer lever 6 operates the neighbouring gear for the arm 21 of the next following numerical unit, so that the carrying over of a ten from a previous numerical place to the next numerical place is effected.

It will be readily understood that the necessity for effecting a transfer from one numerical place to the next (higher or lower depending on whether addition or subtraction is being carried out) can arise from two causes.

In the first case the sector 3 with the counter in the lowered position transmits such a number that the counter wheel 1 in the same numerical place passes from 9 to 0 or 0 to 9. This position is illustrated in Fig. 3, from which it will be seen that the lower end 19 (somewhat hook shaped) of the lever 6 has been brought beneath the projecting pin 20 on the lever 21. When the counter is next raised, as the rack 16 or 16¹ comes into engagement with the counter gear (the sector 3 being disengaged) the end 19 will cause the lever 21 to swing outwards against the action of its spring 22 and allow the lever 24 to swing downwards moving its rack 16, 16¹ forwards by the distance of one tooth i. e. one figure on the counter wheel, thus effecting the transfer.

The second case for transfer arises when the counter is approaching or in the upper or raised position and owing to a transfer (similar to that just described) one or more of the counter wheels must pass from 9 to 0 or 0 to 9. Such a position is shown in Fig. 1. Assuming that the pin 4 is moving in the direction of the arrow 8, then the lever 6 will be forced outwards and the flat portion of the end 19, will press on the pin 20 and operate the levers 21 and 24, and the racks 16, 16¹ as described for the first case.

of transfer. This action takes place successively for all the counter wheels which must pass from 9 to 0 or 0 to 9.

After the first case of transfer has been effected however it is necessary to bring the levers 6 and 11 back to their original position, so that the V shaped projection 7 comes again into the path of the pin 4, so that a fresh transfer can be carried through.

10 The return of these parts is effected during the last phase of the raising of the counter by means of the fixed axle 27 which is located in a slot 28 of the counter casing. The lever 11 just at the end of the upward movement comes against this fixed axle 27 and as a result it is pushed downwards, so that the projection 14 on the lever 6 is removed from the rear surface 15 or shoulder on the lever 11. In this way the locking between 15 the levers 6 and 11 is released and they return under the pull of the spring 12 into the positions shown at Figs. 1 and 4, that is to the initial position.

In the second case of transfer considered 25 the levers 6 spring back to their original position after the pin 4 has passed, owing to the fact that the lever 11 is held in the lowered position by the fixed axle 27.

Just as the levers 6 and 11 have to be 30 brought back to their original positions, so also must the racks 16, and 16¹ together with their operating levers be brought back to their original positions. This is effected not during the last phase of the raising of the 35 counter, but during the next succeeding operation for transmitting a number, and it is effected from a rail 29. This is seen in its normal position at Fig. 1 and in Fig. 3 in a position in which it has been swung as far as possible to the left. In this latter position it has brought back the racks 16 or 16¹, which at this moment through the sinking of the counter have come out of engagement with the gear 2 or 2¹, into the original 40 position by striking against a turned up end 30 of the lever 24 and carrying this lever with it, to its former position.

The rail 29 is operated in the following manner, as will be understood from Figs. 50 5, 6 and 7.

Referring to Fig. 5, which shows the normal position, in which the counter gear is locked to the rack 16 and 16¹, the toothed sector 3 is in that figure in its initial position. The locking rail 29 is carried between lever arms 31, which swing upon a spindle 32. When the lever 31 swings backwards in the direction of the arrow 33, in Fig. 5, the bail 29 comes against the projection 39 55 as already described. The backward movement of the lever 31 in the lowered position of the rack 16, in which this latter is disengaged from the gears 2¹, 2 of the counter and therefore can be moved freely is effected 60 from the machine crank by means of a con-

necting rod 34, actuated thereby, which also actuates the sector 3 as about to be described. The rod 34 is connected to a lever 36 pivoted at 35 and having a transverse member 37 upon which the arms 38 of the toothed sector 3 rest under the pull of a spring.

When therefore the connecting rod is moved in the direction of the arrow 39 in Fig. 5, the lever 38 swings over and with it 75 the cross piece 37, which latter is moved downwards. The toothed sector 3 is therefore unsupported, and under the influence of its spring moves also, so that all the sectors come into the position permitted by their 80 differential mechanism, ready for operation, see Fig. 6, where a sector is shown dotted, set for transmitting a maximum movement. At the same time, the lever 36 is provided with a pin 40, which works in a long slot 85 41, in a connecting bar 42, connected to a pin 43 in another connecting bar 44. This latter bar 44 embraces the pin 45 of an arm of the bent lever 31.

By the connecting bars 42 and 44, a kind 90 of toggle mechanism is formed between the pins 45 and 40.

The supporting of these knee-like joints in the locking position of the racks 16, 16¹ is effected by projecting rollers or pins 46, 95 provided on the lever 6.

As long as the counter is in the raised position and the toothed racks 16, 16¹ are still in engagement with the toothed pinions of the counter, the parts 42 and 44 are at an 100 angle to one other (the dotted position). When however the counter is lowered the rollers 46 are lowered whereby the members 42 and 44 lose their means of support and go over into the extended position. 105 Under the pull of the spring 47. In this position they remain while the return of the lever 38 is taking place, which is effected by means of the sliding rod 34. By the return of the lever 38, the toothed sector 3 is brought back into its initial position. At the same time however the parts 42 and 44 which are in the extended position (at Fig. 7) are caused to move by the pin 40 reaching the upper end of the slot 41, the 110 result being that through the pin 45 the bent lever 31 and with it the rail 29 is swung outwards, that is to say the racks 16, or 16¹ are brought back into their initial position. 115

If then the counter, after transmission of the number, is returned to its initial position, through further raising, then the pin or roller 46 again comes under the link 44 and pushes the parts 42 and 44 back again into the position represented at Fig. 5. At the same time the lever 31, and the rail 29 return to the position shown at Fig. 5. 120

The combined working of the machine is as follows:—The counter is set in the desired position for either addition or subtraction.

tion, after which the items eventually to be transmitted to the counter are set on the keys, causing the differential mechanism connected thereto, to take up the desired 5 positions to limit the movements of their sectors 3, when they are freed subsequently, by the downward movement of the transverse member 37. The machine crank is now operated causing, first the transverse 10 member 37 to be lowered, releasing the sector 3 and allowing them to take up their differentiated positions; the parts are so proportioned and mounted that the counter is now lowered, bringing the counter gears 15 into engagement with the sectors 3 and causing the racks 16, 16¹ which have been in engagement with the counter gears to be brought out of engagement. Upon continuing the operation of the crank, the transverse member 37 is raised. In its upward movement it comes into contact with the tails of all the sectors 3 and turns the sectors. As these are in gear with the counter gears, they transmit to the counter 20 25 the items on the keys. Towards the end of this upward movement of the member 37, the toggle mechanism 40, 42, 44 causes the rail 29 to bring any racks 16, 16¹ which may be in the forward position, back to the original position as previously explained, it being remembered that the racks are free 30 and not in engagement with the counter gears. Should any of the counter wheels 35 pass from 9 to 0 or 0 to 9, as the case may be, the lever 6 is operated as previously explained in the first case of transfer. Upon the final portion of the operation of the machine crank taking place, the counter is raised. This as previously explained effects 40 any transfer the levers 6 for which have been set in position and any consequent transfers which may arise.

I claim:

1. Transfer-mechanism for calculating machines, comprising, in combination; a switching-gear having toothed segments; a counting mechanism adapted to be lifted and lowered and having its cog-wheels in their lower position mesh with said segments; racks located below said cog-wheels; coaxial pivots supporting said racks at their one end; bell-crank levers supported upon pivots of the machine frame and supporting in their turn said coaxial pivots; supporting levers for said counting mechanism; and a common supporting rail coupled with the said racks at their other ends and being adapted to lift and lower them, substantially as described.
  2. Transfer-mechanism for calculating machines, comprising, in combination; a switching-gear having toothed segments; a counting mechanism adapted to be lifted and lowered and having its cog-wheels in their lower position mesh with said seg-
- ments; a plurality of pairs of racks, of which each pair is located below a counting place of the counting mechanism, one of said toothed segments extending between the two members of the co-ordinate pair of 70 racks; coaxial pivots supporting said racks at their one end; bell-crank levers supported upon pivots of the machine frame and supporting in their turn said coaxial pivots; supporting levers for said counting mechanism; and a common supporting rail coupled with the said racks at their other ends and being adapted to lift and lower them, substantially as described.
3. Transfer-mechanism for calculating 80 machines, comprising, in combination; a switching-gear having toothed segments; a counting mechanism adapted to be lifted and lowered and having its cog-wheels in their lower position mesh with said segments; racks located below said cog-wheels; coaxial pivots supporting said racks at their one end; bell-crank levers supported upon pivots of the machine frame and supporting in their turn said coaxial pivots; other 85 levers supported upon pivots of the switching mechanism and supporting in their turn said bell-crank levers; double-levers supported upon pivots of the counting mechanism and having lower arms adapted to bear 90 against the levers supported by the switching mechanism; disks forming members of the counting mechanism; and pins affixed to these disks and being adapted to switch said double-levers; tensioning springs engaging 100 the said bell-crank levers and being adapted to turn them automatically; supporting levers for said counting mechanism; and a common supporting rail coupled with the 105 said racks at their other ends and being adapted to lift and lower them, substantially as described.
4. Transfer-mechanism for calculating 110 machines, comprising, in combination; a switching-gear having toothed segments; a counting mechanism adapted to be lifted and lowered and having its cog-wheels in their lower position mesh with said segments; racks located below said cog-wheels; coaxial pivots supporting said racks at their 115 one end; bell-crank levers supported upon pivots of the machine frame and supporting in their turn said coaxial pivots; other levers supported upon pivots of the switching mechanism and supporting in their turn 120 said bell-crank levers; double-levers supported upon pivots of the counting mechanism; other bell-crank levers also supported by pivots of the counting mechanism, and tensioning springs connecting the lower arm 125 of these levers with said double-levers; laterally projecting lugs at said double-levers; other lugs provided upon the horizontal arms of said bell-crank levers and being adapted to co-operate with the first 130

mentioned lugs; and a stationary rail affixed to the machine frame above said horizontal arms, for the purpose as described.

5. Transfer-mechanism for calculating machines, comprising, in combination; a switching-gear having toothed segments; a counting mechanism adapted to be lifted and lowered and having its cog-wheels in their lower position mesh with said segments; racks located below said cog-wheels; coaxial pivots supporting said racks at their one end; bell-crank levers supported upon pivots of the machine frame and supporting in their turn said coaxial pivots; levers supported by pivots of the switching mechanism; a rail supported by these levers and being adapted to co-operate with said lugs; a mechanism adapted to switch these levers, said mechanism consisting of a push-bar, a lever supported by a pivot of the machine frame, a pin at this lever, a guide-bar having a slot receiving said pin, and a rod connecting said guide-bar with the rail-supporting lever, substantially and for the purpose as described.
- 10 6. Transfer-mechanism for calculating machines, comprising, in combination; a switching-gear having toothed segments; a counting mechanism adapted to be lifted and lowered and having its cog-wheels in their lower position mesh with said seg-
- 15 15 at the upper arms of said bell-crank levers; and a rocking rail supported in the switching mechanism and being adapted to move all said bell-crank levers back into their normal position, substantially as described.
- 20 20 6. Transfer-mechanism for calculating machines, comprising, in combination; a switching-gear having toothed segments; a counting mechanism adapted to be lifted and lowered and having its cog-wheels in
- 25 25 their lower position mesh with said seg-

ments; racks located below said cog-wheels; coaxial pivots supporting said racks at their one end; bell-crank levers supported upon pivots of the machine frame and supporting in their turn said coaxial pivots; levers supported by pivots of the switching mechanism; a rail supported by these levers and being adapted to co-operate with said lugs; a mechanism adapted to switch these levers, said mechanism consisting of a push-bar, a lever supported by a pivot of the machine frame, a pin at this lever, a guide-bar having a slot receiving said pin, and a rod connecting said guide-bar with the rail-supporting lever, substantially and for the purpose as described.

In testimony whereof I affix my signature in presence of two witnesses.
